William Hogan,
Inventor

By *Clarance O'Brien*,
Attorney

UNITED STATES PATENT OFFICE.

WILLIAM HOGAN, OF FILLMORE, UTAH.

HOLDER FOR BEET-TOPPERS' KNIVES.

Application filed July 21, 1924. Serial No. 727,260.

To all whom it may concern:

Be it known that I, WILLIAM HOGAN, a citizen of the United States, residing at Fillmore, in the county of Millard and State of Utah, have invented certain new and useful Improvements in Holders for Beet-Toppers' Knives, of which the following is a specification.

This invention relates to new and useful improvements in holders for knives which are principally adapted for use in the harvesting of beets, and has for its principal object to provide means in connection with the knife for relieving the strain caused by the person using the knife in lifting and cutting beets.

A further object of the invention is to provide a holder for a beet topper's knife of the above mentioned character, wherein a sling is detachably associated with the knife adjacent the handle portion thereof, means being associated with the sling for securing the same in position around the wrist of the person using the knife.

A further object of the invention is to provide a holder for a beet topper's knife of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of my improved device showing the manner in which the sling is used, and

Figure 2 is a top plan view of the knife and sling attachment associated therewith.

In the drawing wherein for the purpose of illustration is shown the preferred embodiment of my invention, the numeral 1 designates a beet topper's knife of any conventional construction having the usual handle 2 at its forward end and provided at its forward end with the downwardly extending pointed member 3 secured at its outer end. The pointed end 3 extends beyond the cutting edge 4 of the knife 1 and is used in lifting the beets from the soil in the manner well known in the art.

In order to relieve the strain caused by the lifting of the beets by the knife and to prevent the person using the knife permitting his hands to be swollen caused from the use of the knife, I provide a sling 5. The sling comprises an elongated strip of leather which is folded intermediate its ends and the free ends thereof are secured together in any suitable manner whereby a loop is provided for permitting the wrist of the person using the knife to pass therethrough. For adjusting the size of the loop in order to enable the sling to be properly supported in position on the wrist of the person using the knife, the adjusting means designated generally by the numeral 6 is slidably associated with the strap. The ends of the strap have secured thereto the attaching hook 7 and the same is adapted for engagement with the registering eyes formed on the free ends of a single strand of wire 8 which is bent back upon itself intermediate its ends and is disposed on opposite sides of the knife blade 1 adjacent the handle 2, the free ends of the strand of wire being looped as illustrated at 9 and 10 respectively in the drawing and adapted to overlap each other so that the looped portions will register and permit the hook 7 to pass therethrough and secure the sling in position on the knife.

The spring wire 8 will fit around the knife 1 adjacent the handle portion 2 in such a manner as to prevent the accidental displacement of the same when the hook 7 is in engagement with the looped portions 9 and 10 and will enable the sling to be supported on the knife at all times. This construction furthermore enables the sling and spring wire to be readily detached from the knife whenever it becomes necessary.

The provision of a sling attachment for a beet topper's knife of the above mentioned character, will enable the person to use the knife more easily and comfortably and will furthermore increase the efficiency in the use of the knife. The sling attachment may not only be used in connection with beet toppers' knives but also may be used for various other purposes such as in connection with hand grabs or hooks or the like.

While I have shown the preferred embodiment of my invention, it is to be understood that various changes in the size, shape and arrangement of parts may be resorted

to without departing from the spirit of the invention and the scope of the appended claims.

Having thus described the invention, what

5 I claim is:—

1. In combination with a lifting element and the handle therefor, a sling, a hook carried by the sling, a strand of wire clamped back upon itself and extending around the lifting element adjacent the handle, the free ends of the wire having loops formed therein, said looped ends overlapping each other and registering to receive said hook, and means associated with the sling for adjusting the size of the loop thereof.

10

2. In combination with a lifting element and the handle therefor, a sling, a hook carried by the sling, a strand of wire clamped back upon itself and extending around the lifting element adjacent the handle, the free ends of the wire having loops formed therein, said looped ends overlapping each other and registering to receive said hook.

2. In combination with a lifting element

and the handle therefor, a sling, a hook carried by the sling, a strand of wire clamped back upon itself and extending around the lifting element adjacent the handle, the free ends of the wire having loops formed therein, said looped ends overlapping each other and registering to receive said hook, and means associated with the sling for adjusting the size of the loop thereof.

20 In testimony whereof I affix my signature.

25 WILLIAM HOGAN.
